UNITED STATES PATENT OFFICE.

GEORGE HENRY ELWELL, OF CLEVELAND, OHIO, ASSIGNOR TO CARR FASTENER COMPANY, OF CAMBRIDGE, MASSACHUSETTS, A CORPORATION OF MAINE.

SNAP FASTENER.

Application filed June 8, 1923. Serial No. 644,414.

To all whom it may concern:

Be it known that I, GEORGE HENRY ELWELL, a citizen of the United States, residing at Cleveland, in the county of Cuyahoga and State of Ohio, have invented certain new and useful Improvements in Snap Fasteners, of which the following is a specification.

My invention relates to improvements in snap fasteners.

The object of my invention is to provide a snap fastener the stud and socket members of which are adapted for selectively fixed relative positions.

With this and other objects in view, as will more fully hereinafter appear, the invention consists in certain novel features of construction and arrangement of parts hereinafter described, illustrated in the accompanying drawing and particularly pointed out wherein patentable novelty is claimed for certain features of the device, it being understood that within the scope of what hereinafter thus is claimed various changes in form, proportion, size and other minor details of the construction can be made without departing from the spirit or modifying any of the advantages of the invention.

The following is the description of an embodiment of my invention reference being had to the accompanying drawing in which Figure 1 is a side view of mounted members in readiness for connected engagement; Figure 2 is a top view of stud member and mounting; Figure 3 is a cross-sectional view of the next preceding figure on line "b—b" of that figure; and Figure 4 is a cross-sectional view of connected members on line "a—a" of Figure 1.

Referring more particularly to the drawing in which similar numbers refer to similar parts, socket member 1 and stud member 2 may be of any of the various types of snap fasteners in so far as the means of connecting the members in fastened position is concerned. The novelty which my invention introduces is a means by which one or both of said fastener members may be slidably mounted and adapted to varying fixed positions within the scope of provision made therefor. In the drawing I preferably show only the stud as the sliding member mounted on base-plate 3 and slidably held on said plate by turned over

edges 4, as shown in Figures 1 and 2. The main portion of stud 2 is preferably a one-piece construction struck up from sheet metal and providing a hollow interior 5 within said stud, as shown in Figures 3 and 4. The head 6 of said stud is perforated to provide opening 7 in the top of said head, said opening communicating with said hollow interior. The base 8 of said stud is a separate piece held in place by the crimped edge of the main portion of the stud, said base being provided with perforation 9 also communicating with said hollow interior. The hollow interior 5 is provided with push-button element 10 operatively accessible through said opening 7 and having a pin 11 provided with free extremity 12, said extremity being adapted to occupy and project from perforation 9, as shown in Figures 3 and 4. Base-plate 3, as shown in Figure 2, is provided with a series of perforations 13 each perforation being adapted to receive in sequence the rounded extremity 12 of pin 11. The socket member 1 and the stud member 2, the latter provided with my push-button element 10 as aforesaid, are so constructed to co-operate that when the socket member 1 is snapped onto the stud member 2 the inner portion of said socket member construction operatively engages the push-button element 10 through opening 7 in the top of the stud head 6 and, when the extremity 12 of pin 11 substantially registers with one of the series of perforations 13 in base-plate 3, said push-button element 10 forces said extremity 12 into said perforation and thereby locks the stud member in a fixed position with regard to base-plate, as shown in Figure 4. In operation it may be preferable to slide the stud member to the desired position and manually press the push-button element until extremity 12 enters one of said series of perforations 13 and then snap the socket member onto the stud member. Disconnected from the socket member the stud member is readily made to slide on base-plate 3 without manually operating the push-button element; for the rounded extremity 12 of pin 11 co-operating with the metal immediately bounding said perforations 13 provides a cam surface adapted to automatically lift the push-button element as the stud member is manually forced along base-plate 3. With the stud member

in fixed position as regards base-plate 3 the connecting and disconnecting of the fastener members are effected in the manner usual to snap fasteners.

It may be advantageous, in the construction of base-plate 3, to substitute a series of indentations for perforations 13. With such substitution, however, extremity 12 of pin 11 need not be rounded provided that such indentations are constructed to provide a cam surface adapted to guide the pin extremity in its travel along base-plate 3.

What I claim is:

1. A snap fastener comprising stud and socket members having an interlocking means; a base-plate upon which one of said members is slidably mounted, said base-plate having an attaching means and also having a series of indentations, and said sliding member having a hollow interior and openings communicating with said interior and certain of said openings adapted to register in sequence with said indentations as said sliding member travels said base-plate; and means operable within said hollow interior and adapted to project through said openings to co-operate with said socket member and said indentations to rigidly maintain said sliding member in a fixed position as regards said base-plate.
2. A snap fastener comprising stud and socket members having an interlocking means; a base-plate upon which one of said members is slidably mounted, said base-plate having an attaching means and also having a series of indentations, and said sliding member having a hollow interior and openings oppositely located and communicating with said interior at its base and interlocking extremity; a shifting filler element with which the interior of said sliding element is provided, said shifting element being adapted for alternate projection through said oppositely located openings and being also adapted for entrance into said indentations in sequence as said sliding member is made to travel said base-plate, the other fastener member in interlocked engagement with said sliding member fixedly engaging said shifting element and maintaining said shifting element in a projected position whereby said shifting element is rigidly held in one of said indentations and said sliding member is thereby maintained in a fixed position as regards said base-plate.
3. An adjustable stud member of a stud and socket fastening device, said stud com-

prising a hollow stud member having openings oppositely located in its head and base and communicating with said hollow interior; a push-button element with which said interior is provided, said push-button element being manually operatively accessible through the opening in the head of said stud to project a pin, with which said push-button element is provided, through said opening in the base of said stud; a base-plate upon which said stud is slidably mounted, said base-plate being provided with an attaching means and also with a series of indentations with which the opening in the base of said stud is adapted to register in sequence as said stud travels said base-plate; and means with which said push-button element is provided, said means being adapted to co-operate with a socket member in interlocked position with said stud member to rigidly maintain said pin projected through the base of said stud and into one of said indentations.

4. A snap fastener comprising stud and socket members having an interlocking means; a base-plate upon which one of said members is slidably mounted, said base-plate having an attaching means and also having a series of perforations, and said sliding member having a hollow interior and openings communicating with said interior and certain of said openings adapted to register in sequence with said perforations as said sliding member travels said base-plate; a movable pin with which said sliding member is provided, said pin having a rounded extremity and being adapted to project through said registering opening and rest in any of said perforations; and means operable within said hollow interior and adapted to co-operate with said socket member and said pin to rigidly maintain said sliding member in a fixed position as regards said base-plate.

5. A sliding stud member of a stud and socket fastening device, said stud having an attaching means adapting said stud to slide upon the substance to which it is attached; a perforation extending through said stud axially; a movable filler with which said perforation is provided, said filler being adapted, when engaged by the socket member, to be projected against said substance thereby maintaining said stud, while said fastener members are in interlocked engagement, in a fixed position as regards said substance.

GEORGE HENRY ELWELL.
